SEALING MEANS AND METHOD FOR WIRE BOUND BOXES

Filed Dec. 6, 1922

INVENTOR.
Edward H. Ludlow
BY Edward Durrell Jr.
ATTORNEY.

UNITED STATES PATENT OFFICE.

EDWARD H. LUDLOW, OF EVANSTON, ILLINOIS, ASSIGNOR TO WIREBOUNDS PATENTS COMPANY, A CORPORATION OF MAINE.

SEALING MEANS AND METHOD FOR WIRE-BOUND BOXES.

Application filed December 6, 1922. Serial No. 605,326.

This invention relates to wire-bound boxes and particularly to sealing means and methods therefor.

Among other objects, the invention is intended to provide a simple and efficient means and method for sealing wire-bound boxes.

In the drawings—

Figure 1 is a perspective view of a seal embodying the invention.

Figure 2 is an enlarged view of a box binding wire with the seal in position to be applied when the free wire ends are twisted together. For clearness of illustration, the box is not shown.

Fig. 3 shows the wire and seal of Fig. 2 after the free ends of the wire and the tongue of the seal have been intertwined.

Fig. 4 shows the twist, with seal applied, hammered down parallel with the binding wire.

Fig. 5 is a perspective view of an ordinary wire-bound box provided with sealing means embodying the invention.

As illustrated in Fig. 5, a wire-bound box usually consists of four separate sections of side material 1 and cleats 2 connected together in foldable relationship by binding wires 3, the free ends 4—4 of which are preferably twisted together as at 5 to complete the continuity of the wire binding. End sections 6 are also usually provided, which end sections preferably rest against the inner faces of the cleats 2 at either end of the box.

A wire-bound box having binding wires attached thereto and completely encircling the same cannot easily be opened without leaving evidence of tampering except by untwisting the intertwined wire ends and then carefully intertwisting them again. Clever pilferers have been able to so manipulate the ordinary wire twist. Applicant provides means for detecting the untwisting and twisting together again of the binding wire ends thus providing a sealing means for a wire-bound box. As shown, such means comprises a small seal adapted to be applied to the twist at the time the free ends of the binding wire are joined and which will disclose evidence of tampering with the twist.

The preferred form of seal comprises a flat body-plate 7 usually of thin metal and circular in shape and a tongue 8 projecting

plate 7; the tongue 8 preferably being cut or stamped out of the body-plate 7 and bent at a right angle thereto as shown in Fig. 1. In applying the seal, the body-plate 7 is placed behind the binding wire and against the box side as shown in Figs. 2 to 5 and the tongue 8 is placed between the wire ends 4—4 as shown in Fig. 2. The operator then twists together the two wire ends 4—4 and the tongue 8, as shown in Fig. 3, and hammers the completed twist down against the side of the box as shown in Figs. 4 and 5. Thus the tongue 8 is intertwined with the free wire ends 4—4 and becomes a part of the twist. If the twist is untwisted the tongue 8 will be so bent and mutilated that it will be almost impossible to replace it in its original twisted position between the wires without leaving evidence of tampering.

It is desirable, in some instances, to make the seal of such thin metal that the untwisting of the twist or an attempted second twisting of the tongue of the seal will cause the tongue 8 to break off from the body-plate 7 thus destroying the seal and leaving evidence of tampering.

It will be noted that the seal is applied at the time the free ends of the binding wire are inter-twisted and becomes a part of the twist. Such a seal and method of applying the same are particularly advantageous in that no additional operation is required in applying the seal; also the seal is held flat against the box side thus eliminating any objectionable projection from the box side to interfere with the handling or storage of the box.

Having described the invention, what is claimed is:

1. Means for sealing a wirebound box comprising a metal plate positioned between a box side and a wire binding and having a metal tongue projecting at approximately a right angle from the plate and intertwined with the free ends of the wire binding; said tongue being formed of thin, soft metal, whereby if the twist is untwisted and again twisted the tongue will be so mutilated and broken as to leave evidence of tampering.

2. Means for sealing a wirebound box comprising a metal plate positioned between a box side and a wire binding and having a tongue projecting therefrom and intertwined with the free ends of said wire binding.

3. Means for sealing a wirebound box comprising a plate having a tongue projecting therefrom and adapted to be intertwisted with the free ends of a box binding wire; said tongue being sufficiently flexible for intertwisting with the wire ends without breaking and frangible when subjected to additional manipulation.
4. Means for sealing a wirebound box comprising a metal member adapted to be intertwisted with the free wire ends of a box binding wire; said member being sufficiently flexible for intertwisting with the
- wire ends without breaking and frangible when subjected to additional manipulation. 15
5. A method of sealing a wirebound box which is characterized by intertwisting with the free ends of a box binding wire a sealing member which is sufficiently flexible for intertwisting with the wire ends without breaking and is frangible when subjected to additional manipulation. 20

In testimony whereof, I have signed my name to this specification.

EDWARD H. LUDLOW.
